UNITED STATES PATENT OFFICE.

IVER JOHNSON AND ANDREW FYRBERG, OF WORCESTER, MASSACHUSETTS;
SAID FYRBERG ASSIGNOR TO SAID JOHNSON.

REVOLVER.

SPECIFICATION forming part of Letters Patent No. 391,156, dated October 16, 1888.

Application filed July 16, 1888. Serial No. 280,067. (No model.)

To all whom it may concern:

Be it known that we, IVER JOHNSON and ANDREW FYRBERG, both of the city and county of Worcester, and State of Massachusetts, have invented certain new and useful Improvements in Revolvers; and we do hereby declare that the following is a full, clear, and exact description thereof, reference being had to the accompanying drawings, forming a part 10 of this specification, and in which—

Figure 1 represents a side view of a revolver embodying our improvements, with one side of the handle removed and a part of the frame broken away to more fully illustrate 15 the improvement upon the parts coming under the same. Fig. 2 is a part side view and part vertical section of so much of the revolver shown in Fig. 1 as is necessary to illustrate our said improvements. Fig. 3 is a view of the 20 under side of the barrel-strap, showing our improved cylinder-holding device, hereinafter more fully described. Figs. 4 and 5 represent, upon an enlarged scale, transverse sections through said barrel-strap and cylinder-holding device, showing the operating parts 25 of said device in different positions; and Figs. 6, 7, and 8 are modifications of our improvements, which will be hereinafter described.

Our invention consists of improvements in 30 the cylinder-holding and hammer-rebounding mechanism of a revolver or other fire-arm. Following is a detailed description thereof with reference to the accompanying drawings.

The cylinder-holding device is arranged in 35 the under side of the barrel-strap *a* and is constructed as follows: In a longitudinal slot or recess in said barrel-strap is fitted a flat spring, *b*, fastened at its forward end at *b'* and having a downwardly-projecting hook or lip, *b''*, at its 40 rear end, adapted to fit over the rear edge of the cylinder, as is best shown in Fig. 2. Between said spring *b* and the barrel-strap is arranged a spindle, *c*, fitted in a transverse opening in said strap, the purpose of which is to 45 operate the spring to unlock the cylinder when it is desired to remove the same from the arm. The spindle is cut out upon its under side next to the spring to form the shoulder *c'*, the short level part *c''*, the bevel or cam *c'''*, and longer level part, *c''''*, and is forced out-

ward longitudinally by the spiral spring *d*, fitted in the bottom of the opening in which the spindle is arranged and adapted to bear upon the inner end of said spindle, as is shown in Figs. 4 and 5.

The spindle is prevented from being forced 55 out of its opening by its shoulder *c'*, bearing against the side of spring *b*. Said spring is in practice made so as to bear upward against the spindle, and said spindle, when in its normal position, is held by the spring *d* with its shoulder *c'* against spring *b*, as aforesaid, and the short level part *c''* against the top of said spring, as is shown in Fig. 2, thus holding the spring down in engagement with the cylinder, 60 and consequently holding the latter in position longitudinally.

When it is desired to release the cylinder to withdraw it from the spindle upon which it turns, the spindle *c* is forced in by pressing 70 upon its outer end, thereby causing the deepest portion of the recess in its under side to be brought in a vertical line with the spring *b*, which allows said spring to assume its natural elevated position, thus raising its hook out of 75 engagement with the cylinder, when said cylinder may then be readily removed.

Various modifications in the foregoing construction may in practice be adopted to accomplish the same result by the use of a spring, *b*, 80 and operating-spindle *d*, and we therefore do not limit ourselves to the exact construction shown and described. As an illustration, one other way is shown in Fig. 6. In adopting this construction the spring *b* is in practice 85 made to bear down instead of up, as in the former instance, and it is provided with a loop, *b''*, on its upper side, through which the spindle passes, and said spindle is cut away upon the top instead of the bottom, with the bevel 90 *c''* reversed, so that when the spindle is forced in the spring will be drawn up to disengage its hook from the cylinder.

Our improvement in the hammer-rebounding mechanism consists in forming a projection, *e*, on the rear edge of the hammer back of its pivot *e'*, adapted to engage with the upper forward end of the hammer-spring *f*, whereby the hammer may be sprung down to strike the firing-pin when released by the trigger 100

mechanism, as usual, and also to cause said hammer to rebound and be held in a partially-
raised position after each operation thereof.
We accomplish the latter result by providing
5 the aforesaid projection on the hammer with
a roll, *g*, or its equivalent, a little above the
level of the hammer-pivot when the parts oc-
cupy their normal positions, as is indicated by
full lines in Figs. 1 and 2, and preferably ar-
10 ranged in a vertical slot, *h*, in said projection,
and by forming a curved hook, *f'*, on the end
of the hammer-spring *f*, adapted to fit over the
front side of said roll, as is best shown in Fig.
2. Said end *f'* is in practice curved suffi-
15 ciently to produce a back-pressure at its ex-
tremity against the front of the roll when the
hammer has been forced down to bring said
roll above the level of the pivot. The upward
pressure of the spring *f* is at this time nearly
20 expended and the back-draft on the hammer,
being above its pivot, causes its upper end to
be drawn back and held in said position, there-
by allowing the firing-pin *i* to spring back, so
as not to retard the rotation of the cylinder
25 when the construction shown in the drawings
is adopted, or to be drawn back when formed
or fastened upon the hammer.

The rebounding action of said hammer may
be regulated to a greater or less degree by
30 means of a screw, *j*, fitted to turn in a threaded
longitudinal opening formed in the front side
of the handle near its lower end, said screw
being adapted to bear against the front side of
the hammer-spring *f*. The back motion of the
35 hammer is increased by turning the screw in
and lessened by relieving the pressure on said
spring.

In Fig. 7 we have shown a cross-connection
40 formed integral with the hammer in lieu of the
roll *g*, while in Fig. 8 studs are formed on each
side of the hammer projection and the curved
end *f'* of spring *f* is made fork-shaped to fit
over the same. The same result, it is obvious,
45 is effected by either construction as by that
first described, and we therefore do not limit
ourselves thereto or to the particular shape of
the curved end *f'*, the essential feature thereof
being to obtain a bearing against the front of
50 the roll to produce the aforesaid back-pressure.

What we claim, and desire to secure by Let-
ters Patent, is—

1. In a revolver, the combination of the bar-
rel strap having a longitudinal slot in its under
side just forward of the usual catch-post
opening, with a flat spring, *b*, fitted in said lon-
55 gitudinal slot and fastened therein at its for-
ward end, also having a hook, *b'*, at its rear
end adapted to fit over the edge of the rear
end of the cylinder, an operating-spindle, *c*,
fitted in a transverse opening in the barrel-
strap in front of the usual catch-bolt opening
60 and having a cam, *c'*, adapted to engage with
the free hook end of the spring *b*, also having
a shoulder, *c'*, adapted to come and hold against
said spring *b* to control the outward longitudi-
65 nal movements of said spindle, and a spiral
spring, *d*, fitted in the spindle-opening and
adapted to bear against the inner end of said
spindle, whereby the spring *b* may be operated
70 independent of the usual catch-post bolt, sub-
stantially as and for the purpose set forth.

2. In a fire-arm, the combination of the ham-
mer having a rear projection provided with
75 a roll, hub, or its equivalent a little above the
level of the hammer-pivot when the parts oc-
cupy their normal positions, with the hammer-
spring having its upper forward end curved
or otherwise shaped to fit over the front side
80 of said roll or its equivalent, whereby a back-
pressure is produced to impart a rebounding
action to the hammer and to hold the same
partially raised, substantially as shown and
specified.

3. In a fire-arm, the combination of the ham-
mer having a rear projection provided with
85 a roll, hub, or its equivalent a little above the
level of the hammer-pivot when the parts oc-
cupy their normal positions, with the hammer-
spring having its upper forward end curved
or otherwise shaped to produce a back-press-
90 ure against said roll or its equivalent, whereby
a rebounding action is imparted to the ham-
mer, and a screw fitted in the front side of the
handle near its lower end adapted to bear
95 against the front side of the hammer spring
to regulate said rebounding action, substan-
tially as shown and specified.

IVER JOHNSON.

ANDREW FYRBERG.
